UNITED STATES PATENT OFFICE.

WILLIAM T. SHERMAN, OF TROY, NEW YORK, ASSIGNOR, BY MESNE ASSIGNMENTS, TO
HENRY L. HUGHES CO., INC., OF NEW YORK, N. Y., A CORPORATION OF NEW YORK.

BRUSH.

1,277,141.

Specification of Letters Patent. Patented Aug. 27, 1918.

Application filed August 21, 1916. Serial No. 115,951.

To all whom it may concern:

Be it known that I, WILLIAM T. SHERMAN, a citizen of the United States, residing at Troy, county of Rensselaer, and State of New York, have invented certain new and useful Improvements in Brushes, of which the following is a specification.

Reference may be had to the accompanying drawings, and the reference characters 10 marked thereon, which form a part of this specification. Similar characters refer to similar parts in the several figures therein.

This invention relates to a type of toilet-brush in which the bristles are supported by 15 an elastic pad or sheet which is inserted and secured in a recess in the brush-back, and preferably so confined by the walls of the recess that the pad is held in buckled position so as to present an outwardly curved 20 or convexed surface from which the bristles divergently project.

As such brushes have heretofore been constructed they have been so readily and injuriously affected by moisture that it was 25 necessary to keep them from contact with water in use in order to reasonably prolong their life.

Certain objects of the present invention are to produce a brush of this type which is 30 practically waterproof, and which will not readily deteriorate and disintegrate though used with water; to tightly secure the edges of the pad within the recess in the brush-back without the use of adhesives and to prevent water from entering the recess through 35 the ventilating aperture with which such brushes are provided.

Other objects will appear in connection with the following description.

40 Figure 1 of the drawings is a plan view of the face of a brush embodying my invention, with a portion of the bristle-supporting pad broken away, and an edge-portion of the pad and the wall of the recess in the brush-back 45 shown in horizontal section.

Fig. 2 is a plan view of the opposite side of the brush with the brush-back partly cut away and shown in horizontal section.

Fig. 3 is a vertical cross-section of the 50 brush taken on the broken line 3—3 in Fig. 2.

Fig. 4 is a vertical cross-section of the brush taken on the broken line 4—4 in Fig. 2.

Fig. 5 is a central, vertical longitudinal

section taken on the broken line 5—5 in 55 Fig. 2.

Fig. 6 is a plan view of the clamp-plates and the operating wedge separated from one another.

Fig. 7 is a plan view of the face of a brush 60 embodying a modified form of my invention, with a portion of the bristle-supporting pad broken away; and an edge-portion of the pad, and the wall of the recess of the brush-back shown in horizontal section. 65

Fig. 8 is a central, vertical longitudinal section of the same taken on the broken line 8—8 in Fig. 7.

Fig. 9 is a horizontal cross-section of the 70 same taken on the broken line 9—9 in Fig. 7, showing one edge of the pad forced past the fingers of the clamp-plate, the opposite edge of the pad not having yet been inserted in the recess of the brush-back.

Fig. 10 is a plan view of the clamp-plate 75 employed in the construction shown in Figs. 7, 8 and 9.

Fig. 11 is a view in perspective of a flexible sheet of vulcanized rubber perforated to receive the bristles in making the elastic 80 pad.

Fig. 12 is a cross-section of the same showing the bristles inserted through the perforations in the sheet with the heads formed by bending over the ends of the bristles 85 exposed upon the back of the sheet.

Fig. 13 is a cross-sectional view showing the heads of the bristles sealed or hermetically embedded in the integral flexible rubber pad formed by vulcanizing upon the 90 rubber sheet, a rubber backing sheet.

Referring to the drawings, 1, represents the brush-back formed with a recess, 2, of a 95 form and size adapted to receive the bristle-supporting pad, 3, the edge-portion of which closely fits within the recess.

The bristles, 4, may be attached to the pad, 3, in any known manner.

The pad is formed of elastic material, preferably soft rubber, and is preferably of such 100 a size that when its edge-portion has been forced into the recess, 2, in the brush-back, the pad will be buckled or curved outwardly, presenting a convexed outer surface from which the bristles divergently project.

The pad is preferably so made that the heads of the bristles are hermetically embedded and sealed therein, which result may 105

be obtained by vulcanizing a thick sheet of rubber upon the heads of the bristles, or by inserting the bristles through apertures in a vulcanized soft rubber sheet with their heads exposed on one side of the sheet, and then vulcanizing a backing sheet upon said perforated sheet covering the heads of the bristles, the two sheets forming an integral construction, as hereinafter described.

10 I have shown the brush-back provided with a preferred form of recess, the wall of which is undercut to form a groove, 5, well adapted to receive the inserted edge of the pad.

15 In carrying out my invention in the form shown in Figs. 1 to 6, I inclose between the pad and the brush-back, clamping-mechanism coöperative with the wall of the recess to clamp thereagainst the edge-portion of 20 the pad.

This clamping-mechanism comprises a pair of relatively movable clamp-plates, 6, and a movable wedge, 7, interposed between said clamp-plates.

25 The outer edge-portion of the clamp-plates, 6, conform approximately to the contour of the side wall of the recess against which the inserted edge-portion of the pad rests, and serve, when the clamp- 30 plates have been forced apart by the wedge, to securely clamp the edge portion of the pad against the wall of the recess.

The clamp-plates and wedge may be made of wood, metal or other suitable material, 35 but I prefer to make the clamp-plates of wood, and the wedge of metal which will not be injuriously affected by water, and to form on opposite sides of the wedge a series of teeth, 8, which become embedded in the 40 edges of the wooden clamp-plates when the wedge is driven in between them and thereby effectively prevent withdrawal of the wedge.

The wedge is preferably provided with a 45 longitudinal slot, 9, through which one or more headed nails or pins, 10, are driven into the brush-back, forming a loose guide for the wedge in its movement, and retaining the wedge in connection with the brush-back while the pad is being inserted and clamped within the recess.

In completing the brush, the clamps, 6—6, are laid within the recess in the brush-back on opposite sides of the wedge which is withdrawn sufficiently to leave a suitable space 55 between the outer edges of the clamp-plates and the side wall of the recess, into which space the edge-portion of the pad is inserted, after which the wedge is driven in between the clamp-plates by means of a pin or other suitable tool, 13, inserted through a perforate opening, 11, formed in the wall of the recess, which opening may also serve as a vent-opening when the brush is in use.

65 When the wedge has been well driven in

between the clamp-plates, the clamp-plates will be so spread apart that their outer edges will tightly clamp the edge-portion of the pad against the wall of the recess, not only securely retaining the pad in position, but making a practically water-tight joint between the pad and the brush-back.

To facilitate the action of the wedge, the clamp-plates may have formed on their inner edges, where engaged by the wedge, inclined surfaces, 12, corresponding with the taper of the wedge.

The ends of the clamp-plates are preferably cut away or rabbeted as at, 14, to permit the plates to lap one another at their ends so as to make contact with the edge-portion of the pad throughout the extent of its internal periphery.

In Figs. 7 to 9, I have shown a brush embodying my invention in preferred form.

In this form of my invention, I employ a clamp-plate, 15, which is preferably made of a single piece of resilient sheet-metal having a serrated edge forming along its periphery a series of fingers or spurs, 16, which are obliquely upturned preferably at an angle of about thirty degrees.

This clamp-plate, 15, is slightly larger than the opening in the face of the brush-back, said fingers or spurs yielding sufficiently to permit the plate to be forced through said face-opening into the recess, after which the fingers spring back to normal position.

After the clamp-plate, 15, has been properly located within the recess, 2, it is secured to the brush-back by screws or nails, 17, leaving the ends of the fingers or spurs, 16, along its periphery at a substantially uniform distance from the side-wall of the recess, 2, which distance is somewhat less than the thickness of the rubber pad which is to be inserted within the recess.

After the clamp-plate, 15, has been thus fastened within the recess in the brush-back, the bristle-supporting pad is symmetrically placed over the face-opening, and its edge portion is, by means of a suitable flat tool or instrument, forced inward between the side-wall of the recess and the ends of the spurs or fingers, 16.

The spurs or fingers, 16, yield inwardly to permit the edge of the pad to be thus inserted; but as soon as the tool or instrument is withdrawn, said spurs or fingers spring outward and embed themselves in the inserted pad, and force the same tightly against the side-wall of the recess.

The thickness of the rubber pad and the distance apart of the spurs or fingers, 16, are such that after the pad has been thus inserted, its edge-portion will be held by the clamp-spurs or fingers, 16, in tight engagement with the side-wall of the recess, so that water cannot enter the recess be-

tween the edge of the pad and the wall of the recess.

The clamp-plate, 15, is preferably made of resilient brass, bronze or other metal, not 5 injuriously affected by water.

For certain purposes of the invention the metal plate, by means of which the rubber pad is secured within the recess of the brush-back may be of any desired form having 10 members, preferably spurs, which directly engage the rubber pad to prevent its withdrawal from the recess.

As ordinarily constructed, brushes, of the type to which this invention relates, have 15 been provided with a ventilating aperture leading to the recess, 2, through the wall of said recess at a point opposite the handle of the brush, as shown at 11, in Fig. 5.

The ventilating aperture thus located permits 20 some water to enter the recess if the body of the brush is immersed in water.

I have shown in Fig. 8, a ventilating opening, 18, leading to the recess, 2, longitudinally through the handle, 19, of the brush, 25 which opening accomplishes the ventilating function without permitting water to pass therethrough into the recess, 2, in any ordinary use of the brush in water.

The brush-back and handle are preferably 30 made of water-proof material. This can be accomplished by making them of molded celluloid, or similar material, or by making them of wood coated with liquid celluloid, or other material not injuriously affected by 35 water.

In making a waterproof bristle-supporting pad, I preferably employ a flexible sheet 21, of vulcanized rubber provided with numerous perforations 22, each adapted to receive 40 one or more bristles as may be desired.

This sheet is formed by vulcanizing the rubber to a degree adapting it to form an elastic support for the bristle, and is preferably 45 provided with the perforations, 22, after being so vulcanized.

The bristles 23, are inserted singly, or in groups comprising two or more, through the perforations, 22, said bristles having on 50 their inner ends, heads, 24, formed in any known manner, preferably by bending over at right angles the inner end of each bristle.

Upon the back of the bristle-filled sheet thus prepared is placed a backing-sheet, 25, of unvulcanized or semi-vulcanized rubber covering the heads, 24, of the bristles, which backing-sheet is then vulcanized upon the bristle-supporting sheet, 21, until the two rubber sheets, 21 and 25, form an integral 60 flexible body of vulcanized rubber.

In making the brush-pad by the method described, I prefer to vulcanize the two sheets together at a temperature somewhat less than the temperature at which the bristle-supporting sheet was previously vulcan-

ized, leaving said bristle-supporting sheet unaffected by such subsequent vulcanization with respect to its flexibility and elasticity.

By the process described, the inner ends of the bristles, and particularly their heads, 70 are hermetically sealed or embedded in an integral body of soft rubber, and are thereby protected from moisture; and there being no seam or joint in the finished pad, there is no tendency for the backing-sheet to separate 75 from the bristle-supporting sheet.

I make no specific claim herein to the construction shown in Figs. 1 to 6 inclusive, as this particular form of my invention is the subject-matter of an application filed by me 80 January 4, 1916, renewed February 25, 1918, Serial No. 219,157, of which prior application the present application is a continuance for certain features of the invention.

What I claim as new and desire to secure 85 by Letters Patent is—

1. A brush having a back provided with a recess, an elastic bristle-supporting pad the edge-portion of which fits within said recess, and means inclosed between the pad 90 and the brush-back coöperative with the wall of the recess to secure the edge-portion of the pad within the recess.

2. A brush having a back provided with a recess, an elastic bristle-supporting pad 95 the edge-portion of which fits within said recess, and having inclosed between the pad and the brush-back, clamping-mechanism including members capable of movement relatively to the wall of the recess and coöperative therewith to clamp thereagainst the edge-portion of the pad.

3. A brush having a back provided with a recess, an elastic bristle-supporting pad the edge-portion of which fits within said recess, and clamping mechanism having resilient 105 members coöperative with the wall of the recess to clamp thereagainst the edge-portion of the pad.

4. A brush having a back provided with a recess, an elastic bristle-supporting pad the edge-portion of which fits within said recess, and clamping-mechanism inclosed between the pad and the brush-back, said clamping-mechanism having a serrated edge 110 coöperative with the wall of the recess to clamp thereagainst the edge-portion of the pad.

5. A brush having a back provided with a recess, an elastic bristle-supporting pad the edge-portion of which fits within said recess, and clamping-mechanism inclosed between the pad and the brush-back, said clamping mechanism having peripherally disposed, 115 resilient members coöperative with the wall of the recess to clamp thereagainst the edge-portion of the pad.

6. A brush having a back provided with a recess, an elastic bristle-supporting pad the edge-portion of which fits within said recess, 120

a clamp-plate secured within said recess, said clamp-plate being of larger dimensions than the opening of said recess, and having peripherally disposed members 5 coöperative with the wall of the recess to clamp thereagainst the edge-portion of the pad, said members yielding to permit the plate to be forced into the recess.

7. A brush having a back of waterproof 10 material provided with a recess, a waterproof soft elastic bristle-supporting pad the edge-portion of which fits within said recess, and clamping-mechanism engageable with the edge-portion of said pad and coöperative

with the wall of the recess to clamp there- 15 against the edge-portion of the pad to make a water-tight joint between the edge of the pad and the wall of said recess.

8. A brush having a back provided with a recess, an elastic bristle-supporting pad 20 the edge-portion of which fits within said recess, and clamping mechanism inclosed between the pad and the brush-back coöperative with the wall of the recess to clamp thereagainst the edge-portion of the pad. 25

In testimony whereof, I have hereunto set my hand this 15th day of August, 1916.

WILLIAM T. SHERMAN.
